O. C. RITZ WOLLER

AUTOMOBILE STEP PLATE

Filed Aug. 5, 1927

Patented Sept. 18, 1928.

1,684,613

UNITED STATES PATENT OFFICE.

OLIVER C. RITZ WOLLER, OF CHICAGO, ILLINOIS.

AUTOMOBILE STEP PLATE.

Application filed August 5, 1927. Serial No. 210,740.

My invention relates to automobile step plates and has for its object the provision of a unitary structure comprising a mat permanently mounted in a suitable metal frame work, with a kick plate rising above the mat along the rear edge thereof.

It is one of the objects of my invention to provide a new and improved form and arrangement of parts for bracing the kick plate in rigid position with respect to the mat, and particularly to produce a structure in which a truss reinforcement effect is provided. It is another object of my invention to provide reinforcements for strengthening the construction in other respects.

It is one of the objects of my invention to improve devices of this type in sundry details hereinafter pointed out. The preferred means by which I have accomplished my several objects are illustrated in the drawing and are hereinafter specifically described. What I believe to be new and desire to cover by this application is set forth in the claims.

In the drawing,—

Fig. 1 is a perspective view of my improved step plate, partly broken away for better showing the construction.

Fig. 2 is a vertical cross section through the plate of Fig. 1, being taken on an enlarged scale at line 2—2 of Fig. 1.

Fig. 3 is a perspective view, partly in vertical section, showing a portion of a plate of modified construction.

Fig. 4 is a vertical cross sectional view taken at line 4—4 of Fig. 3; and

Fig. 5 is a vertical cross sectional view through a portion of a plate of still another modified construction.

Referring now to Figs. 1 and 2 in which one form of my improved device is shown, 10 indicates a frame formed of sheet metal and preferably of soft sheet metal such as aluminum, having an upstanding portion 11 formed integrally therewith at its rear edge,—that is to say, at the edge of the device to be placed adjacent to the body of an automobile upon the running board of which the device is employed. In the construction shown the upstanding portion 11 of the device is in the form of a solid continuous sheet of metal, while the portion 10 is cut out at its center to receive therein a mat 12 the edge portions of which extend underneath the edge portions of the frame 10, as is best shown in Fig. 2. The mat 12 is of any approved type, the mat shown being

formed of rubber and being provided with ribs 13 extending thereacross. The mat 12 is secured in position in the frame 10 by means of a second frame 14 which is also formed of sheet metal, preferably steel. The frame 14 is held in position beneath the mat 12 by means of a plurality of rivets 15 formed integrally with the plate 10, in the construction shown such rivets extending through suitable openings in the frame 14, as is best shown at the right in Fig. 2. The frame 14 is likewise provided with an upstanding portion formed integrally therewith, such upstanding portion being indicated by the numeral 16 (see Fig. 2). The upstanding portions 11 and 16 in the construction shown are rigidly secured together by a plurality of rivets 17, as is clearly shown in Figs. 1 and 2.

The upstanding portions 11 and 16, secured together by the rivets 17, have a truss arrangement with respect to the frames 10 and 14 which are held in rigid position with respect to each other by the rivets 15, this effect being secured by spacing the plate 10 and its upstanding portion 11 at a greater distance from the plate 14 and the upstanding portion 16 at the angle between such parts than at the remaining portions, this effect being increased by arranging the angle between the plate 10 and its upstanding portion 11 of greater size than the angle between the plate 14 and its upstanding portion 16. The construction is further reinforced and strengthened by providing downwardly turned flanges 18 along the front and the sides of the plate 10, and backwardly turned flanges 19 along the top and sides of the upstanding portion 11, such flanges 18 and 19 merging with each other at the angle between the parts 10 and 11. The plate 14 is likewise provided with upwardly directed flanges 20 along the front and sides, such flanges 20 merging with forwardly directed flanges 21 carried by the upstanding portion 16. The plate is still further reinforced by ribs 22 and 23 pressed in the plate 10 along its front and rear edge portions, as is clearly shown in both Figs. 1 and 2.

By the provision of my construction as above described, the step plate is made very strong so as to be capable of withstanding rough treatment for a great length of time without serious danger of being broken. By the provision of the two plates holding the mat rigidly in position between them, I am

enabled to handle the devices to the best possible advantage for packing and shipping in unit form. By providing the rivets 15 formed integrally with the plate 10, the work of assembling the device is kept to a minimum.

Referring now to the form of device as illustrated in Figs. 3 and 4, the construction is substantially the same as that above de-

scribed, and the parts are therefore indicated by the same characters. In this construction, however, the upstanding portions 11 and 16 are formed at substantially the same angle with respect to the plates 10 and 14, the truss effect being attained by reason of the greater length of the sheet material in the bottom plate as compared with the length of the sheet material in the top plate at the angle, as is clearly shown in Fig. 4.

In this construction, however, the upstanding portions 11 and 16 are further strengthened against angular movement with respect to the frames 10 and 14 by means of reinforcements 24 pressed in the sheet metal of the parts 14 and 16 at the angle between such parts at intervals along the rear edge of the device, the metal being pressed backwardly and downwardly for providing an exaggerated truss arrangement at such points as compared with the normal truss arrangement at the remaining points.

Coming now to the construction shown in Fig. 5, a plate 25 is provided corresponding to the plate 10 for holding a mat 26 in position upon a running board. A kick plate portion 27 is provided corresponding with the portion 11 of the constructions above described, the parts 25 and 27 being provided with flanges 28 and 29 which merge at the angle as above described. A reinforcing member comprises a sheet metal plate 30, formed preferably of steel, secured by means of rivets 31 to the upstanding portion 27. The lower edge of the plate 30 is turned forwardly beneath the plate 25 in the form of a flange 32, the forward edge of the flange 32 being in contact with a flange 33 about the opening provided in the plate 25 for securing the device upon the running board. The flange 33 corresponds in a general way with the hollow rivets 15 of the constructions above described. By reason of the rigid bearing of the reinforcing device against both the upstanding portion 27 through the medium of the rivets 31 and the plate 25 through the medium of the flanges 33, an effective truss arrangement is provided in this construction with respect to backward swinging movement of the kick plate 27, the flange 32 being held against forward movement with respect to the plate 25. This is particularly effective when the plate 25 is secured rigidly in position against the running board.

While I prefer the construction as illus-

trated in my drawing and as above described, it is to be understood that I do not wish to be limited to the details of construction as shown except so far as the claims are so restricted by the state of the art; since it will be evident that changes might well be made in the form and arrangement of the parts without departing from the spirit of my invention.

I claim:

1. An automobile step plate, comprising in combination a metal frame having an upstanding portion along the rear edge, a mat secured in said frame, and a metal reinforcing member at the angle between said frame and said upstanding portion in spaced relation thereto and having bearings thereon for providing a truss arrangement therewith.

2. An automobile step plate, comprising in combination a metal frame having an upstanding portion along the rear edge, a mat secured in said frame, and a metal reinforcing member at the angle between said frame and said upstanding portion in spaced relation thereto and secured rigidly to the frame and to the upstanding portion adjacent to the angle at opposite sides thereof for providing a truss arrangement therewith.

3. An automobile step plate, comprising in combination a metal frame having an upstanding portion along the rear edge, a mat secured in said frame, and a sheet metal strip at the angle between said frame and said upstanding portion in spaced relation thereto secured rigidly to one of said parts and having a rigid non-yielding bearing against the other of said parts serving to provide a truss reinforcement against backward swinging movement of the upstanding portion with respect to the frame.

4. An automobile step plate, comprising in combination a metal frame having an upstanding portion along the rear edge, a mat secured in said frame, a sheet metal strip at the angle between said frame and said upstanding portion bent along an intermediate line to provide two portions at a different angle with respect to each other as compared to the angle between the frame and the upstanding portion, and means for securing both of the portions of said strip rigidly to said frame and said upstanding portion for providing a truss reinforcement between said parts.

5. An automobile step plate, comprising in combination a metal frame having an upstanding portion along the rear edge, a mat secured in said frame, a sheet metal strip at the angle between said frame and said upstanding portion bent along an intermediate line to provide two portions at a different angle with respect to each other as compared with the angle between said frame and the upstanding portion, means for se-

- curing one of said strip portions rigidly to one of the angular portions of the frame member, and bearing means carried by the other angular portion of the frame member
- 5 adapted by engagement with the other strip portion to provide a truss reinforcement against backward swinging movement of the upstanding portion with respect to the frame.
- 10 6. An automobile step plate, comprising in combination a metal frame having an upstanding portion along the rear edge, a mat secured in said frame, a second metal frame underneath said first named frame 15 and also having an upstanding portion along its rear edge, upwardly and forwardly directed flange portions along the sides of said second frame member, downwardly and backwardly directed flange portions along 20 the sides of said first named frame member, means for securing the horizontal frame portions rigidly together, and means for securing said upstanding portions rigidly together, the parts being in spaced relation 25 at the angle between the frame and the upstanding portion whereby a truss reinforcing effect is provided.
7. An automobile step plate, comprising in combination two superposed sheet metal frames, a mat extending at its edge portions 30 between said two frames, means securing said frames together serving to hold said mat rigidly in position, and an upstanding kick plate member having a sheet metal portion formed integrally with one of said frames and connected in a truss arrangement with the other frame.
8. An automobile step plate, comprising in combination a sheet metal frame having 35 an upturned flange along its rear edge, a mat 40
- engaging the opening in the frame with its edge portions underlying the frame, a sheet metal plate beneath said mat and secured to said frame at its front and rear edge portions serving to hold the mat rigidly in position and having an upturned flange in spaced relation to said first named flange in rear thereof, and means connecting said flanges rigidly together above said frame whereby a truss reinforcing effect is provided.
9. An automobile step plate comprising in combination a top plate of soft metal provided with downwardly directed flanges about the greater portion of its periphery, a bottom plate of hard metal provided with upwardly directed flanges having a working fit within the flanges of said top plate, said plates being cut out for providing oppositely disposed openings therethrough, means for securing said plates together, and a mat having its edges clamped between said plates in said openings.
10. An automobile step plate comprising in combination a top plate provided with 65 downwardly directed flanges extending substantially completely about the plate and having a large central opening therethrough, a bottom plate provided with upwardly directed flanges extending substantially completely thereabout and having a working fit within the flanges of said top plate, said bottom plate also being cut out to provide a central opening opposite the opening in the top plate, means for securing said plates together, and a mat having its edges clamped between said plates in said openings and being held by the plates in flattened condition.

OLIVER C. RITZ WOLLER.
